United States Patent

Des. 235,745
Patented July 8, 1975

235,745

TRAFFIC HAZARD MARKER

Will Clarke England, 7310 Eastcrest,
Austin, Tex. 78752

Filed Jan. 11, 1974, Ser. No. 432,638

Term of patent 14 years

Int. Cl. D10—06

U.S. Cl. D10—109

FIG. 1

FIG. 1 is a perspective view of a traffic hazard marker showing my new design;

FIG. 2 is a top plan view thereof;

FIG. 3 is a bottom plan view thereof;

FIG. 4 is a vertical cross-section view taken on line 4-4 of FIG. 2;

FIG. 5 is a fragmentary cross-section view taken on line 5-5 of FIG. 4.

I claim:

The ornamental design for a traffic hazard marker, substantially as shown.
